LOOM AND METHOD OF WEAVING.

Application filed July 21, 1925. Serial No. 45,016.

The present invention relates to looms, and more particularly to high speed, weft replenishing looms, and to an improved method of weaving.

5 The object of the invention is to reorganize and improve weft replenishing looms in order to carry out a new method of weaving by virtue of which the cloth is woven at a much higher speed than has heretofore been practiced in weft replenishing looms. To the above ends the present invention consists in the loom and method of weaving hereinafter described and particularly defined in the claims.

15 In the accompanying drawings illustrating the preferred form of the loom of the present invention, and at the same time capable of carrying out the method of weaving herein contemplated, Fig. 1 is an end elevation of 20 the left end of a loom; Fig. 2 is a section through the lay and a part of the frog; and Fig. 3 is a front elevation of a portion of the lay and the parts attached thereto.

The loom forming the subject of the present 25 invention is described as follows: The frame 1 supports the loom parts, the lay 2 being carried by the swords 3 in the usual manner, actuated by the pitman 4, connected to the crank 5 of the crank shaft 6. The motor or pulley 30 shaft 7 is supported in the usual position, and carries the pick cam 8. The harnesses 10 are supported and actuated in any convenient manner. The warp stop detector 11 is supported at the rear of the loom. The warp 35 beam 12 is carried in the usual manner, and the warp 13 passes over the whip roll 14, thence through the warp detector 11 and harnesses 10, through the reed of the lay and over the breast beam to the take-up, neither of 40 which latter are shown.

There are three important features of this loom which contribute to its successful operation at high speeds; that is to say, from 15% to 20% higher than the ordinary weft replenishing loom speeds now obtaining in general use. These three devices are the pre-positioning pick cam 8, the variable shuttle box tension controlling means, indicated in a general way by the reference character 15, 45 and the anti-bang contrivance, by virtue of which, when a shuttle fails of boxing, the whip roll is pulled forward to prevent a smash.

The pre-positioning pick cam is illustrated 50 and described in the application of Clare H.

Draper for an Improvement in looms, filed March 6, 1925, Serial No. 13,573. According to this invention the pick cam 8 is provided with a cam surface 16 of peculiar new shape. The pick ball first engages this cam surface at about the point 17, and as soon as the cam moves forward it lifts the pick ball slightly until the point 18 is reached, thereby advancing the picker stick from the end position to the picking point. Thereupon, at the point 18 the picking portion 20 of the pick surface 16 lifts the pick ball, rapidly accelerates it to the desired extent, and causes it to throw the shuttle with the necessary velocity across the loom. The important feature of this pick cam is that by virtue of which it pre-positions the shuttle before picking, so that the shuttle is always picked as near as may be from the same position called the "picking position."

70 The shuttle tension controlling mechanism, indicated in a general way by the reference character 15, is constructed substantially as described in the application of Clare H. Draper and Jonas Northrop, filed December 3, 1924, Serial No. 753,611. It is described as follows: The shuttle binder 21 is of the usual form, and is activated by the binder fingers 22 to cause pressure to be exerted upon the shuttle in the box. The shuttle fingers are 75 mounted on the arms 23 of the dagger shaft 24, mounted in brackets on the lay in the usual manner. The dagger 25 is carried by the dagger shaft 24, and adapted to engage the steel 26 of the frog 27 in the usual manner. 80 An inertia arm 28 is secured to the dagger shaft 24, and enlarged in the form shown to constitute a weight. The lay 2 is provided with a dagger stop 30 of sheet metal, bolted to the lay beam and protected by a layer 31 85 of leather. The end of this dagger stop is adapted to engage the dagger 25 to prevent upward overthrow, in the usual manner. The hub 32 of the inertia arm 28 is loosely mounted on the dagger shaft 24, being held from 90 endwise movement in one direction by the collar 33, and in the other direction by engagement with the face 34 of the sword 3. Limited rotational movement of the hub 32 on the dagger shaft 24 is permitted, owing to the 95 fact that the collar 33 of the hub 32 is shoudered, as shown in Fig. 2, the collar 33 being provided with the shoulder 35, and the hub 32 of the inertia arm 28 being provided with the shoulder 36. Both the shoulders 35 and 36 100 105 110

are recessed, as shown best in Fig. 2, and receive in their recesses the spring 37. The recess in the shoulder 36 is closed, while the recess in the shoulder 35 is open, and the spring bottoms against an adjusting screw 38, secured in place by a check nut 40. This affords means for varying the tension of the spring. It will be seen that when the lay moves forward, the lag of the inertia arm 28 tends to compress the spring 37, which pressure is thereby exerted through that spring upon the collar 33 of the dagger shaft 24, so that the inertia of the weight is yieldingly applied in one direction to the dagger shaft. 15 In the opposite direction of motion of the lay, the abutting surfaces of the inertia arm at the collar 33 are not cushioned, there being no spring interposed between them. These surfaces are indicated as in contact on the line 20 41, Fig. 2.

The anti-bang will be understood from reference to the patent to Jamieson dated February 23, 1904, No. 753,198. The specific embodiment thereof illustrated in the drawings is described as follows: The frog 27 is slidably mounted on the frame of the loom, a rubber block 42 being provided to cushion the last portion of the forward movement of the frog. The frog is connected with the whip roll by the following devices: The rods 43, one on each side of the loom, are pivotally attached to the frogs at 44, and extend rearwardly outside of and parallel to the frame of the loom, and are provided at their rear 25 ends with lever collars 45, loosely mounted on the rods and secured in adjusted position by means of the adjusting nuts 46. These lever collars 45 are provided with ears 47, which engage recesses in the side levers 48, pivotally mounted at 50 in the brackets 51, secured to the frame of the loom. These levers 48 extend in a generally vertical direction, and are provided at their upper ends with the flats 52, which engage the ends of the whip roll shaft 40 53. These shafts are carried in blocks 54, slidably supported in the slideway 55 of the brackets 56, supported from the rear of the loom, as shown in Fig. 1. Strong anti-bang springs 57 are interposed between the blocks 51 and the ends of the slideway 55, a recess being formed in the casting to receive one 45 end of the spring, and the block being provided with a spring seat to receive the other end of the spring. The whip roll shaft 53 carries two arms 58 which support the whip roll 14 in their outer ends, the whip roll being mounted on a rod which is received in a block 60, carried in a slot 61 in the arms 58. A spring 62 is interposed between the block 60 and the end of the slot 61, and normally tends to hold the whip roll at the extreme end of the slot 61. This spring is a light spring, and compensates for variations in the tension of the warp during weaving. Its operation is 55 substantially that illustrated and described

in the Durkin patent dated April 24, 1888, No. 381,617. The anti-bang springs 57 are strong, heavy springs, and are required to be such in order to operate to resist the blow of the lay in the event of the failure of the 70 shuttle to be boxed. These springs bottom, that is to say, the coils of the springs come in contact with each other, before the lay reaches front center. There is, therefore, no possibility of the lay smashing the warp by means 75 of a trapped shuttle.

It is to be observed that the forward movement of the whip roll is about double in amount the forward movement of the frog, which, being somewhat less than the forward 80 movement of the lay during the time of engagement of the dagger with the steel of the frog, is ample to provide slack warp to prevent a smash.

The mode of operation of the loom requires, 85 perhaps, a little further elucidation with respect to the operation of the shuttle box tension controlling devices. This mechanism operates by virtue of the inertia arm 28 to decrease the shuttle box tension at the front 90 center to facilitate bobbin transfer. It also operates to decrease the binder pressure during picking of the shuttle, and to provide a certain maximum shuttle tension during boxing acting to apply pressure to the binders 95 greatest in amount at the earliest time of arrival of the shuttle in the box, and less and less in amount the later the time of shuttle arrival.

The pre-positioning of the shuttle in the 100 shuttle box operates to move the shuttle to its picking point so that it is located at the picking point when the picking operation takes place, which is coincident with the release of the shuttle box tension at that time, so as to 105 reduce the amount of work required in picking. This contributes to uniformity of time of shuttle flight.

The anti-bang construction cooperates intimately with the shuttle actuating and shuttle 110 tension controlling devices, because on the failure of a shuttle to reach the box, the shuttle tension permits the dropping of the dagger, so that the latter strikes the frog and causes the whip roll to be pulled forward, thereby 115 preventing a smash.

From the foregoing it will be seen that there is an intimate combination and interaction between the several features of this loom. The pre-positioning of the shuttle contributes to accuracy of time of shuttle arrival, the release of the shuttle tension during picking, and the provision of the greatest shuttle tension at the time of earliest shuttle arrival provides a manner of securing greater nicety of 120 operation of the loom, and the interaction of the shuttle tension devices with the anti-bang is practically assured by the connection of the frog which is actuated from the shuttle tension devices to the anti-bang. 125 130

The method of weaving which this loom is capable of carrying out contemplates the forming of the warps in sheds, passing a shuttle filling through the sheds to lay filling therein by first placing or positioning the shuttle in picking position and holding it with light pressure during picking, arresting the shuttle at the end of its flight by means acting to apply the greatest friction to the shuttle at the earliest time of arrival, and less and less friction with later and later shuttle arrival, and the employment of means to prevent the destruction of the warps by the flapping of the shuttle in the shed. As an incident to this method, the reduction of the tension on the shuttle during transfer facilitates the transfer by permitting the shuttle to move freely under the influence of the transfer hammer.

In spite of the precautions which this method contemplates of reducing the friction by which the shuttle is held at the time of picking, and pre-positioning the shuttle preparatory to picking, some variations in the initial velocity of the shuttle do inevitably occur, arising from wear or other variation in the operation of the loom, and in order to take care of such variations in the initial velocity of the shuttle which result in an earlier or later arrival thereof at the opposite side of a warp, the variable friction means are provided for arresting the shuttle at the end of its flight, such means acting to vary the capacity thereof so as to gradually bring the shuttle to rest, such friction means acting to present the greatest resistance to the shuttle at the earliest time of arrival at the end of its flight, and a lesser and lesser amount with later arrival.

While higher speed of the loom may be secured by the use of a variable shuttle tension operating to reduce the tension in picking, to increase it at shuttle arrival and decrease it gradually with later arrivals, with pre-positioning of the shuttle preparatory to picking, the best embodiment of the method contemplates the employment of a device for preventing warp breakage upon shuttle trapping, and these three features of the present method produce a new method of weaving of great value and importance by reason of the greatly higher speeds at which the method may be practiced beyond those ordinarily capable of use in weaving.

This application is a continuation in part of the application of the present inventor filed May 29, 1925, Serial No. 33,833, for a Method of weaving.

Having thus described the invention, what is claimed is:

1. A weft replenishing loom of the bobbin changing type having, in combination, a lay provided with a shuttle box, weft replenishing mechanism, binders for the shuttle box, pressure applying means acting to

apply pressure to the binders greatest in amount at the earliest time of arrival of the shuttle in the box and less and less in amount the later the time of shuttle arrival, picking means for picking the shuttle having provision for positioning the shuttle preparatory to picking, and connections between the shuttle tensioning means and the warp for loosening the warp when the shuttle is trapped in the shed. 70

2. A weft replenishing loom of the bobbin changing type having, in combination, a hopper, a lay provided with a shuttle box, binders for the shuttle box, pressure applying means acting to apply pressure to the binders greatest in amount at the earliest time of arrival of the shuttle in the box, and less and less in amount the later the time of shuttle arrival, and of reduced amount during shuttle picking, picking means acting to 80 position the shuttle preparatory to picking, and an anti-bang connected with the shuttle tensioning means acting upon trapping of the shuttle in the shed to free the warp of tension. 85

3. A weft replenishing loom of the bobbin changing type having, in combination, a hopper, a lay provided with a shuttle box, means for applying pressure to the binders acting to decrease the binder pressure at the 95 time of picking, and picking means having provision for pre-positioning the shuttle preparatory to picking. 90

4. A weft replenishing loom of the bobbin changing type having, in combination, a hopper, a lay having a shuttle box, a binder for the shuttle box, tension applying means having provision for decreasing the shuttle box tension at front center to facilitate transfer, for decreasing the shuttle tension 100 at picking time, and picking means having provision for pre-positioning the shuttle preparatory to picking. 105

5. A weft replenishing loom of the bobbin changing type having, in combination, a lay provided with a shuttle box, a binder, pressure applying means for the binders acting to increase the pressure of the binder from front center to back center, to increase it from top center to back center, to decrease 110 it from back center to bottom center, and to decrease it from bottom center to front center, and picking means having provision for pre-positioning the shuttle preparatory to picking. 115

6. The method of weaving which consists in forming warps in sheds, passing a shuttle carrying filling through the sheds to lay filling therein by first placing or positioning the shuttle in a certain position and holding it 125 with light, frictional pressure during picking, arresting the shuttle at the end of its flight by frictional means acting to apply greatest friction to the shuttle at the earliest time of arrival, and less and less friction 130

with later and later shuttle arrival, the warp being normally held under weaving tension and released from such tension upon the failure of the shuttle to complete its flight through the shed.

7. The method of weaving cloth which consists in forming warps into sheds, passing a shuttle carrying filling through the sheds to lay filling therein by first placing

10 or positioning the shuttle in a certain position and holding it with light, frictional pressure during picking, arresting the shuttle at the end of its flight by frictional means acting to apply greatest friction to

15 the shuttle at the earliest time of arrival, and less and less friction with later and later shuttle arrival, and removing the weaving tension on the warps upon failure of the shuttle to completely traverse the shed.

20 8. The method of weaving cloth which consists in forming warps into sheds, passing a shuttle carrying filling through the sheds to lay filling therein by first placing

or positioning the shuttle in a certain position and holding it with light, frictional pressure during picking, and arresting the shuttle at the end of its flight by frictional means acting to apply greatest friction to the shuttle at the earliest time of arrival, and less and less friction with later and later shuttle arrival.

9. A weft replenishing loom of the bobbin changing type having, in combination, a hopper, a lay provided with a shuttle box a binder for the shuttle box, means for applying pressure to the binders acting to decrease the binder pressure at the time of picking, and means acting to apply pressure to the binders greatest in amount at the earliest time of arrival of the shuttle in the box, and picking means having provision for pre-positioning the shuttle preparatory to picking.

In testimony whereof I have signed my name to this specification.

CLARE H. DRAPER.
